VALVE SEAT GRINDING IMPLEMENT

Filed June 9, 1939

UNITED STATES PATENT OFFICE

2,203,143

VALVE SEAT GRINDING IMPLEMENT

Samuel H. Haas, Los Angeles, Calif.

Application June 9, 1939, Serial No. 278,231

6 Claims. (Cl. 51—241)

My invention relates generally to grinding devices and more particularly to the particular type of tool or instrument designed for grinding the valve seats of internal combustion engines and forming the subject matter of my co-pending application for U. S. Letters Patent, filed February 23, 1939, Serial No. 257,807.

The principal objects of my invention are, to generally improve upon the construction of the valve seat grinding implement disclosed in my aforesaid co-pending patent application, as well as other forms of similar tools, to provide improved means for effecting a positive driving connection between the stem of the implement and the grinding wheel and further, to provide an automatic expansion ball bearing for that portion of the stem of the implement that extends into the fixed guide and bearing that is formed integral with the cylinder block below the valve seat and, which receives the depending stem of the valve that controls the part that is surrounded by said stem.

By providing an automatic expansion bearing for the stem of the implement, said stem will during operation oscillate on a fixed axis and have a firm and substantial bearing in the bore of the valve stem guide, even though said bore may be somewhat larger in diameter than the diameter of the stem of the grinding implement. A further object of my invention is, to provide a valve seat grinder that is especially applicable for use in connection with fluid pressure operated motors that impart oscillating rotary motion to a shaft or other member to which the stem of the valve seat grinding implement is detachably connected.

With the foregoing and other objects in view, my invention consists in certain novel features of construction and arrangement of parts that will be hereinafter more fully described and claimed and illustrated in the accompanying drawing in which:

Fig. 1 is a side elevational view of a grinding implement constructed in accordance with my invention and showing the same in position to grind a valve seat.

Fig. 2 is an elevational view of the grinding implement with parts thereof in vertical section.

Fig. 3 is a horizontal section taken on the line 3—3 of Fig. 2.

Fig. 4 is an enlarged vertical section taken on the line 4—4 of Fig. 2.

Fig. 5 is a horizontal section taken on the line 5—5 of Fig. 4.

Fig. 6 is a perspective view of a modified form

of the driving washer utilized between the oscillating stem of the implement and the grinding wheel, also showing the upper portion of the grinding wheel.

Referring by numerals to the accompany drawing which illustrates a preferred embodiment of my invention, 10 designates the body of a conventional fluid pressure actuated motor of the type that imparts oscillating rotary motion to its shaft 11 and, detachably connected to the lower end of shaft 11 is the upper portion of a link 12 comprising a flat plate having its lower portion 13 bent a quarter turn so that it occupies a position at right angles to the upper portion of said plate.

The lower portions 13 of this link is detachably connected in any suitable manner to the upper end of a stem 14 that carries the grinding wheel.

The construction just described and which is fully described in my above mentioned co-pending patent application functions as a universal joint between the driving shaft 11 and stem 14 so as to enable the motor and its shaft to function properly in driving stem 14, even though the axes of the stem and shaft are not in direct longitudinal alignment. A portion of the stem 14 a short distance below its upper end is externally threaded as designated by 15 and, a short portion 16 of said stem just below this threaded portion is formed square or non-circular in cross section in order to receive and hold against rotation, a driving washer 17.

This driving washer is in the form of a metal disc provided with a centrally arranged aperture 18 shaped so as to receive the non-circular portion 16 of the stem, thus providing a positive driving engagement between the stem and washer and, portions of the washer around the opening therein are indented or pressed downwardly to form depending studs 19. These studs are adapted to enter corresponding recesses or depressions 20 that are formed in the upper surface of the grinding wheel 21, the latter being of the conventional type and preferably formed of pulverized abrasive material and having on its lower portion an inclined or beveled face 22 that engages and grinds the valve seat.

Grinding wheel 21 is provided with an axially disposed aperture 23 that receives an enlarged portion 24 of stem 14 just below the non-circular portion 16 and, the under face of the grinding wheel rests on a flange 25 that is formed on the stem just below the enlarged portion 24. After the grinding wheel has been positioned on the stem and the driving washer 17 positioned

on top of the grinding wheel with the studs 19 positioned in the recesses 20, a washer 26 is positioned on the stem and bears directly on top of the driving washer and a nut 27 is tightly screwed onto the threaded portion 15 of the stem to firmly maintain the grinding wheel and the driving washer in position on the stem.

A modified form of the driving washer is illustrated in Fig. 6 and, in this construction a driving engagement between said washer and the grinding wheel is effected by means of short fingers 28 that are formed integral with and depend from the edge of the washer and, which fingers enter recesses 29 that are formed in the top of the grinding wheel when the parts are assembled for use.

Formed in the lower portion of the stem 14 is an axial bore 30, the lower portion of which is threaded for the reception of a short threaded 20 plug 31 and, the latter being provided in its lower end with a slot 32 for the reception of the point of a screw driver or like implement. Resting on the upper end of the plug 31 is the lower end of an expansive coil spring 33, the upper end thereof 25 bearing against the lower end of a plunger 34 that is adapted to slide freely in the upper portion of the bore 30 and, the upper end of this plunger is cone-shaped as designated by 35.

Formed through the wall of the stem surrounding 30 the upper portion of the bore 30 are apertures 36 and, loosely arranged in each of these apertures is a small ball 37 of hard metal. These balls are normally forced outwardly by the cone-shaped upper end 35 of plunger 34, which latter tends to move upwardly under the pressure exerted by spring 33 and, the outward movement 35 of these balls is limited by retaining lips 38 that are formed around the outer ends of the apertures 36.

40 As a result of the construction just described, the balls 37 function as an expanding anti-friction bearing between the lower portion of the stem 14 and the valve stem guide in which said stem is positioned while the grinding implement 45 is in service and thus, the lower portion of the stem is maintained for oscillating rotary motion on a fixed or definite axis, even though the opening in the valve stem guide is larger in diameter than the diameter of the stem of the grinding implement. In addition, the balls carried by the 50 lower portion of the stem provide an effective expanding anti-friction bearing between the stem and the fixed valve stem guide.

55 In the use of my improved valve seat grinding implement, the lower portion of the stem 14 which functions as a pilot is inserted downwardly into the valve stem bearing in the cylinder block and the implement is moved downward until the 60 inclined face 22 of the grinding wheel engages the inclined seat of the valve.

65 Motor 10 in operation imparts oscillating rotary motion to shaft 11 and this motion is imparted through the universal joint member 12 to stem 14 and parts carried thereby, so that the grinding wheel 21 engages and grinds the valve seat to the desired degree.

70 It has been demonstrated in practice that by imparting oscillatory rotary motion to the grinding wheel, a much smoother and evenly finished surface is produced on the valve seat than where the grinding wheel is continuously rotated in one direction.

Inasmuch as the driving washer 17 is located 75 on the upper portion of the stem of the imple-

ment and engages the upper surface of the grinding wheel, the parts of the implement are capable of being readily assembled or taken apart and, as the driving washer is mounted on a non-circular portion of the stem and depending portions of the washer engage in recesses in the top of the body of the grinding wheel, a very effective and positive driving connection is provided between the stem and grinding wheel.

The construction of the implement is such as 10 to permit grinding wheels or discs of different sizes to be interchangeably used on the stem of the implement and with the driving washer that is carried thereby.

Thus it will be seen that I have provided a valve 15 seat grinding implement that is relatively simple in construction, inexpensive of manufacture and very effective in performing the functions for which it is intended.

It will be understood that minor changes in 20 the size, form and construction of the various parts of my improved valve seat grinding implement, may be made and substituted for those herein shown and described, without departing from the spirit of my invention, the scope of 25 which is set forth in the appended claims.

I claim as my invention:

1. In a valve seat grinding implement, a stem 30 provided with a shoulder and with a non-circular portion located above said shoulder, a grinding wheel positioned on said stem and resting on said shoulder, there being depressions formed in the top of said grinding wheel, a driving washer provided with a non-circular aperture for the reception of the non-circular portion of said stem, members depending from said driving washer for engagement in the depressions in the top of the grinding wheel and means on the stem for locking the driving washer to the grinding wheel and for locking said grinding wheel against said shoulder.

2. In a valve seat grinding implement, a stem, a grinding wheel removably mounted on the upper portion of said stem, a driving washer arranged above said grinding wheel and having 45 driving engagement with said stem, said washer having driving engagement with said grinding wheel and an expansive anti-friction bearing arranged in the lower portion of said stem for engaging the valve stem guide and bearing in which 50 the lower portion of said stem is positioned.

3. In a valve seat grinding implement, a stem, a grinding wheel removably mounted on the upper portion of said stem, a plurality of apertures 55 formed in the lower portion of said stem, balls loosely arranged in said apertures and spring pressed means for engaging and tending to move said balls outwardly in said openings.

4. In a valve seat grinding implement, a stem, 60 a grinding wheel removably mounted on the upper portion of said stem, a plurality of apertures formed in the lower portion of said stem, balls loosely arranged in said apertures, a plunger arranged for sliding movement in the lower portion 65 of said stem for engaging said balls and tending to move the same outwardly and a spring for exerting upward pressure against said plunger.

5. In a valve seat grinding implement the combination with a stem, of a grinding wheel 70 removably mounted on the upper portion of said stem, a driving washer disposed above said grinding wheel and having driving engagement with said stem, said washer having driving engagement with said grinding wheel and anti-friction 75

bearings carried by the lower portion of said stem for engaging the valve stem guide and bearing in which the lower portion of said stem is positioned.

5. In a valve seat grinding implement the combination with a stem, of a grinding wheel removably mounted on the upper portion of said

stem and anti-friction bearings carried by the lower portion of said stem for engaging the valve stem guide and bearing in which the lower portion of said stem is positioned while the device is in use.

5

SAMUEL H. HAAS.
